PNEUMATIC PRESS FOR CEMENTING SOLES
ON SHOES

John L. Thompson, Somerville, Mass., assignor
of one-half to George Laganas, Lowell, Mass.,
and one-half to Lena A. Wilson, Somerville,
Mass.

Application July 30, 1932, Serial No. 626,397

5 Claims. (Cl. 12—33)

My present invention relates to pneumatic presses for use in cementing outer soles on shoes.

While I am aware that pneumatic presses of this character are not broadly new, yet, in most prior devices it has been necessary for the operator to inflate the press after placing the shoe in its proper position, and while this method is effective and produces the same result, much time is consumed in small shops not equipped with continuous air pressure.

In my present invention I have developed a pneumatic press which may be continuously inflated, or in other words is never deflated from one operation to another and which is very fast in operation.

The principal object in my invention is an improved pneumatic press for shoes and the like where outer soles are to be cemented to the shoe.

It is also an object to provide a device of the character set forth in which the shoe contacting element of the clamping means which holds the shoe against the inflatable element is adjustable to accommodate for different positions of the same shoe and easily replaceable to accommodate for shoes of different size, yet in which such element is positively supported by the clamping mechanism when in unclamped position.

It is a further object to provide an improved inflatable structure in which the pneumatic tube will be positively held in its proper position at all times and at the same time protected from deterioration due to wear, moisture, dust, etc.

Other objects and novel features comprising the construction and operation of my invention will appear as the description of the same progresses.

Referring to the drawing illustrating my invention,

Fig. 1 is a plan view of the press in operation, and

Fig. 2 is a cross-section taken on the line 2—2 of Fig. 1 showing the press in operation.

Referring more in detail to the drawing, 10 indicates the bottom of the base casting which is supported at the rear by a flanged portion 11, and at the front by a leg member 12. Around the sides and front of the casting 10 is a flange member 13 to which are bolted binding straps 14. Between the binding straps 14 and flange 13 is placed a protective covering 15 which is securely held between the flanges 13 and 11 and the binding straps 14. The binding straps 14 also extend down over the back of the press to the edge of the flange 11 and throughout their entire length are provided at intervals with holding bolts 16.

Within the covering 15 and between the covering and inner side of the base 10 are placed a pair of pneumatic tubes 17 each provided with a valve 18 through which the tube is inflated. A binding strap 14 is secured to the base and holds the covering 15 securely thereto along the central portion between the two pneumatic tubes.

The rear flange 11 is further provided with a strap member 19 under which the back edge of the covering 15 is secured.

The upper structure of the press comprises a clamping bridge member 20 horizontally disposed across the press and provided at either end with vertical rod members 21 terminating at their lower extremities with offset clamp members 22 adapted to fit under the edge of the flanges 13 at either side of the press.

As shown in Fig. 1 the press consists of two units such that a pair of shoes may be operated upon at a time as is usually the requirement but for purposes of description the description of one will suffice for both each being a duplicate of the other.

Directly over the center of the pneumatic tube 17 is the clamping mechanism which holds the shoe in place while the cementing operation is in progress. This mechanism comprises a bridge member 23 having integral downwardly extending toe piece 24 and an integral downwardly extending heel piece 25, the upper surface of which bridge member is formed with a dovetail slideway adapted to receive the ball end of a threaded shaft member 26, such that the bridge 23 may be adjusted in any position longitudinally on the pneumatic cushion which the operator desires. One end of this slideway is left open so as to permit the ready removal of the bridge member 23. For the sake of convenience in referring to the slideway, the term "innermost wall" may be used to denote that inner wall of the slideway which is directly opposite and parallel to the open side of the slideway and which in the present embodiment as shown in Figure 2 is the bottom wall of the slideway. The threaded shaft 26 is engaged in a threaded opening in a boss 27 located in the upper bridge member 23 and is further provided on its top with a pair of cross handles 28.

In operation, the shoe 29 first having a last 30 inserted within it is placed upon the pneumatic cushion, then the shaft 26 is screwed down with the toe piece 24 and heel piece 25 in contact respectively with the toe of the shoe and the heel of the last, thus compressing the pneumatic tube 17 and sinking the bottom of the shoe with the sole 31.

piece 31 into the cushion provided by the pneumatic tube until the entire bottom surface of the sole 31 is in contact and under pressure of the cushion.

5. To release the press all that is necessary is to reverse the screw shaft 26 a few revolutions and the press is ready for another operation.

If desired the clamp members 22 may be solidly attached to the bottom of the flanges 13 but I 10 prefer to leave them detachably connected thereto as shown so that the bridge 20 may be easily adjusted.

Having thus described my invention what I claim as new is:

15. 1. In a pneumatic press for cementing shoe soles, a base portion, a flexible air container member mounted against said base, a lower bridge member adapted to engage the toe of a shoe supported by said container and the upper heel portion of a last inserted in said shoe, said bridge member having a dovetail slideway on the upper side of and extending longitudinally thereof, an upper bridge member positioned above said container, and a compression screw threadedly engaging said upper bridge member and having a rounded enlarged end portion in slidable interlocking engagement with said dovetail slideway on the lower bridge member, whereby said lower bridge member will be supported by said compression screw when in its unclamped position and may be adjusted relative thereto to properly engage a shoe and last.

2. In a pneumatic press for cementing shoe soles, a base, an inflatable structure mounted thereagainst, said base and said structure having coacting parts for anchoring the structure to the sides, front, and rear of the base, a lower bridge member having downwardly extending spaced parallel integral parts adapted to engage the toe 35 of a shoe supported by said container and the upper heel portion of a last inserted in said shoe, said bridge member having a dovetail slideway on the upper side of and extending longitudinally thereof, an upper bridge member positioned above said container, and a compression screw threadedly engaging said upper bridge member and having an enlarged end portion in slidable interlocking engagement with said dovetail slideway on the lower bridge member, whereby said lower bridge member will be supported by said compression screw when in its unclamped position and may be adjusted relative thereto to properly engage a shoe and last.

3. In a pneumatic press for cementing shoe soles, a base portion, a flexible air container member mounted against said base, a lower bridge member adapted to engage the toe of a shoe supported by said container and the upper heel portion

of a last inserted in said shoe, said bridge member having a dovetail slideway on the upper side of and extending longitudinally thereof, an upper bridge member positioned above said container, and a compression screw threadedly engaging said upper bridge member and having a rounded enlarged end portion in slidable interlocking engagement with said dovetail slideway on the lower bridge member, whereby said lower bridge member will be supported by said compression screw when in its unclamped position and may be adjusted relative thereto to properly engage a shoe and last, said dovetail slideway being open at one end to permit ready removal of said lower bridge member from the compression screw.

4. In a pneumatic press for shoe soles, a base portion, a flexible air container member mounted against said base portion, a lower bridge adapted to engage the toe of a shoe supported by said container and the upper heel portion of a last inserted in said shoe, an upper bridge positioned above said lower bridge, and a compression screw threadedly engaging said upper bridge, said lower bridge and the lower end of said screw having coacting parts for slidably securing said lower bridge to the lower end of said screw, one of said parts having a slot opening toward the other part and forming a slideway and having portions projecting from the sides of said slot at a position spaced from the innermost wall thereof, and the other of said parts having a reduced portion extending between said projecting portions and an enlarged portion carried by said reduced portion and positioned in said slideway inwardly of said projecting portions, whereby said enlarged portion will be slidably retained within said slideway to slidably support said lower bridge from the lower end of said screw.

5. In a pneumatic press for shoe soles, a base portion, a flexible air container member mounted against said base portion, a lower bridge element adapted to engage the toe of a shoe and the upper heel portion of a last inserted in said shoe, an upper bridge member positioned above said element, a compression element threadedly engaging said upper bridge member, one of said elements being provided with a slot constituting a slideway, said slideway having a portion at a position remote from its innermost wall which is relatively narrower than the portion adjacent said wall, and the other of said elements having a part extending into said slideway through said relatively narrow portion and having an enlarged part positioned inwardly of said relatively narrow portion and coacting therewith for slidably supporting said lower bridge element on the lower end of said compression element.

JOHN L. THOMPSON.
